WEIR KILBY CORPORATION, OF NORWOOD, OHIO, A CORPORATION OF OHIO

RAILROAD HIGHWAY CROSSING

Application filed May 5, 1931. Serial No. 535,174.

This invention relates to railroad road or highway grade crossings and provides metallic floor plates for the road or highway approximately in plane with the tread surface of the railroad track rails, the floor plates removably secured upon a substructure supported upon and spiked to the cross ties. In the present invention the substructure constitutes beams, preferably angle iron, parallel with the track rails and mounted upon chairs or brackets spiked to the cross ties, the chairs at the rails of a form to provide rests for the rails and tie together the substructure at opposite sides of the rails, without connecting directly to the rails.

An object of the invention is to provide a railroad crossing of metallic floor plates interposed between the rails of the track and at opposite sides thereof removably interlocked upon a substructure secured to the cross ties.

Another object of the invention is to provide a railroad highway grade crossing constituting metallic plates removably interlocked with and upon a metallic structure, the interlock affected by movement of the plates in a direction preferably longitudinal of the rails and retained against displacement by deflected ends of the plates bearing upon and secured to the cross ties.

Another object of the invention is to provide a railroad highway grade crossing of metallic plates secured to a substructure fixed to the ties, the plates being of considerable length adapting the average width of crossing to be reached by a pair of plates with their relative opposite ends deflected and secured to the cross ties.

Another object of the invention is to provide a railroad highway grade crossing of metallic plates removably fixed to a substructure, the substructure at opposite sides of each rail connected together by means extending beneath the rail at the ties and providing rests for the rail.

Another object of the invention is to provide a railroad highway grade crossing with a minimum number of plates adapting each plate to be deflected at one end to bear upon a cross tie and spiked thereto.

Further objects and advantages of the invention will be more fully set forth in a description of the accompanying drawings, in which:

Figure 1 is a top plan view of a railroad highway grade crossing constructed according to the invention with the floor plates of a dimension reaching one-half of the width of the roadway.

Figure 2 is an enlarged section on line 2—2, Figure 1.

Figure 3 is an enlarged section on line 3—3, Figure 1.

Figure 4 is a perspective view of one of the chairs connecting the substructure at opposite sides of the rails.

Figure 5 is a detailed cross section of the substructure at the rail, showing a modified form of chair.

Figure 6 is a top plan view of the chair shown as in Figure 5.

In railroad highway grade crossings it is essential to maintain the plates of surface members in continuous relation in a proper plane with the tread surface of the rails of the track so a level and uniform surface is presented to traffic. The structure must yield and deflect with the rails under a heavy moving weight to avoid distortion, and the plates at the outside of the rail connected with the plates along the inside of the rail, free from direct connection with the rail, and readily removable for track repair and ballasting.

With the present invention the plates are of considerable longitudinal dimension so that only two plates are required to meet the width of the average highway and in this capacity materially differs from the prevailing crossings using metallic plates. The plates therefore, for each width of the center of the highway can have their outer ends deflected to rest upon and be spiked to the cross ties thus securing each plate to a cross tie. The number of plates required is therefore reduced to a minimum and capable of being more securely connected with the substructure with less liability for accidental displacement or of becoming loosened by the breaking of one or more of the fastening or securing connections.

Referring to the drawings, 1 indicates the cross ties of a railway track which are preferably uniformly spaced apart at a definite center spacing to facilitate in installing the substructure for the highway crossing which is fabricated at a manufactory. The numerals 2—2 indicate the railway rails.

The substructure for the highway crossing comprises angle irons or beams 3 extending longitudinally of the rails or parallel therewith, and in the preferred form comprises a pair for each width of floor plate 4 and disposed at the opposite longitudinal ends of the floor plates.

The longitudinal supports or angle irons remote from the rails are each provided with a plurality of angle brackets or chairs 5 while those adjacent the rails are fixed to U-brackets or chairs 6 spiked with the rail to the cross ties. The brackets or chairs bear a relative spacing corresponding to the cross tie spacing adapting each chair to bear directly upon the cross tie with the vertical flange thereof fixed to the angle irons.

The chairs 6 for the supports or beams adjacent the rails being of U-form provide a connecting cross plate portion for connecting the substructure at opposite sides of the rail and serve as rests for the rail.

At the inside of each rail non-metallic filler strips 7 and 8 are interposed between the web of the rail and the longitudinal beams of the substructure to appropriately space the same and provide a wheel flange groove 9 with the non-metallic filler forming the base thereof. An insulating strip 10 is interposed between the crossing sections, longitudinally centrally of the track insulating one section from the other which is necessary when the rails are utilized as conductors for electric signal service. The strip is preferably of a dimension allowing the lower end to bear upon the cross ties and the upper end flush with the top of the floor plates.

The floor plates 4 are preferably long flat steel plates, plain or toe checked on the upper side, removably secured or interlocked with longitudinal beams of the substructure by means of downwardly offset clips 11 depressed from the plate at suitable spacing apart along the opposite longitudinal margins of the plate. The clips are arranged each to engage into a notch 12 cut into the horizontal flanges of the angle irons 3 and interlocked therewith by slidably longitudinally shifting or moving the plate, the clip hooking under an edge or shoulder of the beam formed by the notching so that when the plate is interlocked with the beam it is securely held against vertical displacement.

It is obvious, however, that other means may be employed for removably connecting the plates to the substructure but the means above disclosed has been found to be very efficient and simple.

One end of each plate is depressed or inclined downwardly to bear upon a cross tie to which it is spiked securing the plate against longitudinal movement. This also gives finish to the opposite ends of the highway and permits the plates to be partially directly anchored or secured to the ties. For the width of a single track, four plates are generally employed, two between the rails and one at each of the opposite sides of the track so that the crossing is divided into two sections, the sections separated by the insulating strip 10, with the sections about one rail tied or joined by the U-chair which supports the rail. For the average width of the highway, the floor plates are of a length requiring only two plates with the depressed ends at relatively opposite sides and abuttingly engaging at their inner ends. Two plates longitudinal of the track can be conveniently handled for a 30 foot span of highway. This is of considerable advantage as it provides greater stability and it is easier to maintain a uniform surface with less liability of the plates becoming loosened. It also reduces the number of plates and facilitates in making an installation.

The plates are moved inwardly for interlocking the same with the longitudinal beams of the substructure, thus the plates at one side of the highway move in a direction opposite to those on the other side of the highway. This enables the plates at one side of the highway to be removed without disturbing those at opposite sides leaving half of the highway open for traffic, while repairs are being made to the track or track bed for the other half of the highway. Each individual plate or any number thereof at one side of the highway can be removed without disturbing the others.

The highway crossing is free from fastening connection with the rails adapting the rails and crossing to yield independent of each other when depressed under weight imposed thereon, any creeping action of the rails does not effect the crossing structure and there is no opportunity for the one to distort the other.

Before assembling or installing the crossing in the track it is desirable to have the ties properly located and the top face of all the ties should be in the same horizontal plane to give the supports for the plates uniform bearing and a proper plane.

In Figures 5 and 6, a modified form of chair is disclosed, and adapting the same to serve as a toe brace for the base of the rail formed by bending a portion of the chair upon itself. The structure and configuration of the chair may be variously modified from the design herein illustrated. The number of floor plates may be increased or decreased to meet various crossing dimensions, and the fastening means for removably connecting the plates to the

substructure of a type which would require the plates to be shifted laterally instead of longitudinally of the rails.

Having described our invention, we claim:

- 5 1. A railway highway grade crossing, comprising, rails and cross ties, beams extending parallel with the rails mounted upon and secured to the cross ties, a pair thereof longitudinally adjacent opposite sides of a rail,
- 10 chairs for said pair of beams bearing upon and fixed to respective ties connecting the beam to the rail and providing a rest for the rail, and plates supported upon and secured to said beams, the plates each having an end depressed to overlie the corresponding ends of the beams and to bear upon and be secured to a cross tie.
- 15 2. A railway highway crossing, comprising, beams longitudinal with the railway rails fixed to the cross ties, and plates supported upon said beams interlockingly engaged therewith against vertical displacement, the interlock affected by movement of the plates longitudinal of the rails, and each
- 20 25 plate depressed at one end for securing the plate to a cross tie and against displacement.

In witness whereof, we hereunto subscribe our names.

GEORGE FERNEDING.
